UNITED STATES PATENT OFFICE.

ANDREW H. DAVIES, OF CONNEAUT, OHIO, ASSIGNOR TO GENERAL ELECTRIC COMPANY, A CORPORATION OF NEW YORK.

DESIGN FOR A HANGER OR THE LIKE.

45,859.

Specification for Design.

Patented June 2, 1914.

Application filed May 23, 1913. Serial No. 769,498. Term of patent 14 years.

To all whom it may concern:

Be it known that I, ANDREW H. DAVIES, a citizen of the United States, residing at Conneaut, in the county of Ashtabula, State of Ohio, have invented a new, original, and ornamental Design for Hangers or the like, of which the following is a specification, reference being had to the accompanying drawing, forming part thereof.

In the drawing, Figure 1 is a front elevation of a hanger embodying my design. Fig. 2 is a side elevation, certain accessory parts used with the hanger being indicated in dotted lines. Fig. 3 is a view on a smaller scale showing three such hangers in various positions and illustrating in dotted lines how they may be employed for the suspension of an illuminating bowl.

I claim:

The ornamental design for a hanger or the like, as shown.

In witness whereof, I have hereunto set my hand this 16th day of May, 1913.

ANDREW H. DAVIES.

Witnesses:

EDWARD R. CRAWFORD,
HARRY W. HAWKE.
